Patented July 18, 1922.

UNITED STATES PATENT OFFICE.

OSWALD C. LEGER, OF LOS ANGELES, CALIFORNIA.

WINDING MECHANISM FOR SPRING MOTORS.

1,423,230.

Specification of Letters Patent. Patented July 18, 1922.

Application filed December 23, 1921. Serial No. 525,288.

To all whom it may concern:

Be it known that I, OSWALD C. LEGER, a citizen of Canada, residing at Los Angeles, in the county of Los Angeles and State of California, have invented a new and useful Winding Mechanism for Spring Motors, of which the following is a specification.

This invention relates to mechanism which can be applied to a spring motor to wind the same. One use of the invention is to effect the winding of the spring motors of phonographs.

In the particular instance illustrated, the mechanism is operated by movement of the lid of the phonograph.

The accompanying drawings illustrate the invention:

Fig. 1 is a perspective view of the upper portion of a phonograph, with the invention installed thereon.

Fig. 2 is an enlarged side elevation of Fig. 1, portions of the cabinet being shown in section, a portion of the reproducer being broken away and the turntable omitted.

Fig. 3 is an enlarged plan section on the line indicated by 3—3, Fig. 2.

Fig. 4 is an elevation, partly in section, on the line indicated by 4—4, Fig. 3.

Fig. 5 is an enlarged detail of the means for connecting the rack with the lid.

Fig. 6 is a plan detail of the latch, the rack being shown in section. The latch is shown in solid lines in rack-engaging position and is indicated in broken lines in retracted position.

The phonograph cabinet is indicated at 7 and includes a hinged lid 8 as is customary with certain styles of phonographs. The hinge of the lid is indicated at 9. The spring motor is indicated in general by the character 10 and is provided with the usual winding gear 11. It is customary to rotate the gear by a pinion, such as that indicated at 12, mounted on a shaft 13. The shaft is journaled in bearings 14, 15 and is screw-threaded as indicated at 16 for connection with the usual motor-winding handle, not shown. In this instance the screw-threads 16 are internal, but in some phonographs said screw-threads are external.

The construction so far described is old and is therefore well understood by those skilled in this art and the invention which may be constructed, if desired, as an attachment, will now be described.

Detachably engaging the screw-threads 16

is the screw-threaded end 17 of a shaft 18. The screw-threads 16, 17 thus constitute coupling means for the two shafts. On the shaft 18 is mounted a floating forked bracket 19 and between the forks of said bracket is a spur gear 20 which is loosely mounted upon the shaft 18. On the gear 20 is mounted a tubular casing 21 provided on its inner face with ratchet teeth 22. The teeth 22 are adapted to be engaged by a sliding pawl 23 mounted in a slot 24 in the shaft 18 so as to slide transversely of said shaft. This form of pawl and ratchet is not new and therefore its construction and operation will be readily understood without further description. The shaft 18, bracket 19, gear 20 and casing 21 are held assembled by a cotter pin 25 extending through the outer projecting end of the shaft 18. The bracket 19 forms a closure for the outer end of the casing 21 so that the pawl will be retained in operating position within the casing.

Engaging the gear 20 is a rack 26, the teeth thereof being indicated at 27. The rack 26 is held against disengagement from the gear 20 by a guide block 28 which is secured by screws 29 to the bracket 19 between the forks thereof and in alignment with the gear 20. It is to be noted that the block 28 is spaced sufficiently from the gear 20 to permit the rack to be interposed between the gear and the block, not only, but to produce an appreciable space between the rack and block when said rack is held in close engagement with the gear, said space being indicated at 30. If the block 28 were to fit closely to the rack, there would be a tendency for the rack to bind against the block when the rack is reciprocated but, because of the space, the bracket, since it floats, turns sufficiently around the shaft 18 to permit the rack to engage the block near one end or the other according as the rack is raised or lowered.

The rack projects through an opening 31 in the cover 32 of the motor housing, and the upper end of said rack is pivoted at 33 to an angle plate 34 which is adapted to be fastened by screws 35, or their equivalents, to the inner face of the lid 8 of the phonograph. The pawl and the ratchet teeth are constructed so that upon downward motion of the rack the teeth 22 slip by the pawl, and upon upward motion of the rack the appropriate tooth engages the pawl, thus turning the shaft 18 to effect winding of the spring motor 10 in a manner readily understood. It

will be readily understood that the pawl and the ratchet teeth could as readily be constructed to effect winding of the motor on the downward movement of the rack.

5 Phonographs of the type having hinged lids are generally provided with collapsible arms for supporting the lids in raised position, for convenience of the operator in placing records on and removing them from the 10 turn-tables. In this invention I have provided a device which enables me to hold the lid in raised position so that such collapsible arm may be eliminated and this device comprises an arm 36 pivoted at 37 to the housing 15 cover 32 in position to project over the opening 31 and selectively engageable with the rack teeth 27 to hold the rack in an adjusted position against downward movement, thus holding the lid 8 in raised position. The arm 20 36 may be provided with a knob or handle 38 to make it more convenient to operate.

The invention operates as follows: When it is desired to reproduce a record, assuming that the lid of the phonograph is closed, the 25 lid will be raised, thus winding the motor. Then the latch will be engaged with the rack to support the lid in the raised position. The desired record will then be placed on the

turntable. The brake holding the turntable against rotation will then be thrown off and 30 the latch will be released from the rack and the lid allowed to shut.

I claim:

1. In a winding mechanism for spring motors, the combination of a shaft having 35 coupling means at one end, a gear loose on the shaft, means operative by rotation of the gear in one direction only to drive the shaft, a floating bracket mounted on the shaft, a guide carried by the bracket, and a rack between the guide and gear engaging said gear.

2. The combination with a phonograph having a spring motor and a lid, of a rack pivotally connected with the lid, means operated by endwise movement of the rack to 45 wind the motor, and means mounted on the phonograph and engageable with the rack teeth to support the rack against the pressure of the lid.

Signed at Los Angeles, California, this 50
21st day of December, 1921.

OSWALD C. LEGER.
